[57] CLAIM

The ornamental design for a combined cap and pump closure, as shown and described.

DESCRIPTION

FIG. 1 is a perspective view of a combined cap and pump closure showing my new design;

FIG. 2 is a side elevational view thereof;

FIG. 3 is a top plan view thereof;

FIG. 4 is a bottom plan view thereof; and

FIG. 5 is an elevational view showing the side opposite that seen in FIG. 2.
